UNITED STATES PATENT OFFICE

JACOB R. OSBORN, OF DU BOIS, PENNSYLVANIA

RUNNER BLOCK AND MOUNTING MEANS THEREFOR

Application filed November 17, 1925. Serial No. 69,629.

This invention relates to improvements in runner blocks for grinding machines and means for securing said blocks to a grinding head.

5 Heretofore it has been the practice to unite two or more runner blocks in a single unit by casting them as integral portions of a common base-plate or attaching bar.

It is an object of the present invention to 10 cast the runner blocks as individual units and detachably secure them to separate base-plates or attaching elements by means of which they may be mounted on the grinding head. In the preferred form of the invention the attaching elements will be in the 15 form of bars of sizes sufficient to accommodate two or more runner blocks.

The invention includes reinforcing means which assist the fastening devices, by which 20 the blocks are secured to the mounting elements, in preventing relative rotation about axes perpendicular to their opposed contacting surfaces.

Blocks made in accordance with this invention 25 materially reduce the degree of distortion experienced in the casting of a plurality of runner blocks as an integral unit, thereby greatly reducing the amount of time which must be spent in working the faces of the 30 blocks down to a common plane surface adapted for grinding. The invention also makes it possible to construct the mounting elements of a material different from that used in the making of the runner blocks, 35 whereby each part may be formed of the material most suitable for its intended purpose; and, if desired, the surfaces of the runner blocks and their attaching members may 40 be machined to accurate sizes, thereby further eliminating the amount of time necessary to prepare the grinding head for grinding after a new set of blocks has been mounted thereon.

45 In the drawings illustrating the preferred form of the invention,—

Figure 1 is a fragmentary bottom view of a grinding head with runner blocks embodying the invention applied thereto.

50 Fig. 2 is a sectional view through a por-

tion of the grinding head illustrated in Fig. 1.

Fig. 3 is a bottom view of an attaching element or mounting bar with two runner blocks mounted thereon.

Fig. 4 is a side view of the mounting bar and runner blocks illustrated in Fig. 3, the third runner block being indicated in a position slightly detached from the mounting bar.

Fig. 5 is an end view of the mounting bar and runner blocks illustrated in Figs. 3 and 4.

The invention in its preferred form as illustrated in the above-described drawings 65 comprises an attaching element or mounting bar 10, to one surface of which may be secured one or more individual runner blocks 11. These blocks may be of any suitable shape but in the preferred form herein disclosed they are illustrated as being of oblong 70 form having slightly inclined opposite side walls 12, conical end walls 13, and parallel plane bases 14 and grinding surfaces 15.

The mounting element 10 may be of such 75 size and form as to accommodate one or any desired number of the runner blocks 11. In Fig. 3 is illustrated an attaching element in the form of a rectangular bar of a size such as to accommodate three runner blocks spaced in end to end relation therewith. These 80 blocks may be securely but detachably fastened to the attaching bar by means of suitable fastening devices herein disclosed as screws 16 inserted through openings 17 in the mounting bar and having threaded engagement with tapped openings 18 provided therefor in the bases of the runner blocks.

If desired, reinforcing means may be provided to aid the fastening devices 16 in preventing relative rotation between each block 90 and the mounting element about an axis perpendicular to their contacting faces. Such reinforcing elements may comprise abutments extending from one of said elements 95 into engaging relation with portions of the other. In the preferred form herein disclosed the reinforcing elements for each runner block comprise parallel abutments 19 projecting slightly from the surface of the mounting element 10 and separated by a dis- 100

tance such as to receive and snugly embrace the opposite sides of the bases of the runner block, as clearly indicated in Figs. 3 and 5.

It will be apparent that the forms of the runner blocks may be varied as well as the manner of forming the interlocking relation between the bases of the runner blocks and the reinforcing elements. It is of importance, however, that the engaging faces of the runner blocks and the reinforcing elements should be so disposed as to prevent relative rotation between the runner blocks and the mounting element about an axis perpendicular to their contacting faces.

Any appropriate means may be provided whereby the mounting element with its runner blocks attached thereto may be detachably secured to a grinding head. In the form herein disclosed, openings 20 are provided in portions of the attaching element which are not covered by the bases of the runner blocks, said openings being adapted to receive screws 21 (Fig. 1) by means of which the attaching element and the runner blocks mounted thereon may be affixed to the usual deck 22 of wood or other appropriate material secured in the usual manner to the under surface of a grinding head 23.

As heretofore stated, the attaching elements may be varied in size and form to accommodate any desired number of runner blocks and the attaching elements and mounted runner blocks may be applied to the deck of the grinding head in accordance with any desired arrangement, one arrangement being illustrated in Fig. 1.

It will be apparent from the foregoing description that runner blocks made in accordance with this invention may be accurately dimensioned and are free from the degree of distortion commonly experienced in the casting of a plurality of blocks and their supporting element as a single unit. Further accuracy of form may be attained, if desired, by machining the working faces of the runner blocks and the attaching member. This greater accuracy of form results in economy of time in that the grinding head to which a new set of blocks has been applied may be much more quickly worn down to a plane grinding surface preparatory to the grinding of the material to be worked upon. When the runner blocks have been worn down as closely as practicable to the attaching element, the mounting element may be removed from the grinding head and the remaining base portions of the runner blocks may be detached from the attaching element by removing the screws 16, after which a new set of runner blocks may be applied to the attaching element. This results in a marked degree of economy over the combined runner blocks and bases of the prior art of which it is necessary to scrap the mounting elements or attaching bars whenever a set of blocks

becomes so worn as to have to be replaced by new ones.

Since the mounting bars or attaching elements 10 do not have to be scrapped when the runner blocks are renewed but may be used continuously, it becomes practicable to make them from material best adapted for the intended purpose, even though at a somewhat increased cost, and to machine them to accurate form. The increased cost of producing accurate mounting members would be more than made up in the saving of time in working the surfaces of the applied grinding blocks down to a common level preparatory to a grinding operation.

The invention is not intended to be limited to the specific form herein selected for purpose of illustration but should be regarded as including variations and modifications within the scope of the appended claims.

What is claimed is:

1. The combination, with a grinding deck, of a plurality of grinding runner blocks, a common mounting bar therefor, individual attaching means whereby each of said blocks may be detachably secured to the exposed face of said bar, and means whereby said bar and the attached blocks may be detachably secured to said deck, said bar-attaching means being readily accessible, for application and removal, from the block-receiving surface of the deck.

2. The combination, with a grinding runner block, of a mounting element by which it may be secured to a grinding head, detachable attaching means passing through the base of said element into and secured within the base portion of said block, and openings in parts of said element not covered by said block to receive fastening devices whereby it may be detachably secured to a grinding head.

3. The combination, with a grinding deck, of a grinding runner block, a mounting element therefor, means to prevent relative rotation between said block and said element about an axis perpendicular to their opposed faces, said means comprising abutments extending from one of said parts into engaging relation with parts of the other, readily removable attaching means whereby said block and said element may be detachably secured together in positions such as to render said abutments effective, and means whereby said element, with said block secured thereto, may be detachably secured to said deck, said element-securing means being accessible, for application and removal, from the block-receiving surface of the deck.

4. The combination, with a grinding runner block having a base of non-circular outline, of a mounting element therefor, means to prevent relative rotation between said block and said element about an axis perpendicular to their opposed faces, said means comprising

abutments projecting slightly from the block-receiving surface of said element and so positioned as to snugly embrace oppositely disposed portions of the base of said block, detachable attaching means whereby said block may be secured to the portion of said element lying between said abutments, and means whereby said element, with said block mounted thereon, may be detachably secured to the block-receiving surface of a grinding head, said element-securing means being accessible, for application and removal, from the exposed surface of the element.

5. A mounting element whereby a grinding runner block may be secured to a grinding head, said element having abutments projecting slightly from its block-receiving surface and so positioned as to snugly engage portions of the base of said block, when mounted, 10 and prevent relative rotation about an axis perpendicular to said surface, openings in the portion of said element intended to be covered by the mounted block to receive removable fastening devices whereby the block 15 may be detachably secured thereto, and openings in parts of said element not intended to be covered by the mounted block to receive removable fastening devices whereby the element 20 may be detachably secured to a grinding head.

In witness whereof, I have hereunto signed my name.

JACOB R. OSBORN.
